UNITED STATES PATENT OFFICE.

WILTON E. DARROW, OF SUTTER CREEK, CALIFORNIA.

CONCENTRATING APPARATUS.

No. 906,205.

Specification of Letters Patent.

Patented Dec. 8, 1908.

Application filed April 20, 1908. Serial No. 428,240.

To all whom it may concern:

Be it known that I, WILTON E. DARROW, a citizen of the United States, residing at Sutter Creek, in the county of Amador and State of California, have invented certain new and useful Improvements in Concentrating Apparatus; and I do declare the following to be a full, clear, and exact description of the same, such as will enable others skilled in the art to which it appertains, to make and use the same, reference being had to the accompanying drawings, and to the characters of reference marked thereon, which form a part of this application.

This invention relates to improvements in concentrators used in separating valuable metals from their ores, and particularly to a device in which low grade ores or mill tailing may be made to yield their value in such a cheap, simple and effective manner as to render it profitable to work the same, this application being intended as an improvement upon my Patent No. 898331, dated September 8, 1908.

Further objects of this invention are to produce a rotary tray or shelf concentrator having rotating fabric-covered trays or shelves independently adjustably and interchangeably mounted in rows or tiers on central supports, such trays or shelves revolving or rotating around a central stationary pulp supply mechanism having certain launders or feed connections for each row or tier of trays, whereby the pulp will be suitably and evenly distributed onto said trays. Also to produce a double system of spray mechanism for said trays whereby sprays will be disposed on each side of said shelves or trays and spray thereon from both directions. Also to produce a device having an admirably constructed and operated system of distribution for the pulp whereby the best concentrating results can be obtained from the action of the fabric covered trays or shelves.

These objects and minor ones I accomplish by means of a stationary pulp supply means around which is disposed a track or runway on which are wheel mounted a plurality of upright supports suitably connected with a driving belt or cable, on which supports are centrally adjustably and interchangeably mounted rows or tiers of concentrating shelves or trays, such pulp feeding mechanism being suitably disposed to discharge on such trays or shelves as they rotate; also by such other and further con-

struction and relative arrangement of parts as will appear by a full perusal of the following specification and claims.

In the drawings similar characters of reference indicate corresponding parts in the several views.

Figure 1 is a top plan view of the complete device. Fig. 2 is a cross section taken on a line $x-x$ of Fig. 1. Fig. 3 is a fragmentary view of a tray supporting means. Fig. 4 is a cross sectional view of a tray showing method of detachably supporting the same on an adjustable band.

I will now describe in detail the general construction and arrangement of the improved concentrator, then describe separately the whole operation thereof.

Referring now more particularly to the characters of reference on the drawings 1 designates a main supporting frame around the lower end of which is disposed a circular track or runway 2. Running on said track 2 are wheels or rollers 3 supporting vertical uprights 4 carrying a plurality of inwardly projecting arms 5 spaced apart in tiers, each tier carrying a circumferentially disposed inclined plate or ring 6 having dependent hook-like projections 7 upon which rest the inner ends of circumferentially disposed concentrating trays or shelves 8, said trays or shelves having angle iron sides 9 with centrally located dependent hooklike projections 9^a by means of which the complete concentrating trays consisting of 8, 9 and 9^a are removably attached centrally and adjustably on the supports 4 by means of the circumferentially disposed bands 10 said bands being adjustable vertically in slots 11 in said supports 4 and having adjustment nuts 12 for locking said bands 10 in any desired fixed position.

Secured near the tops of the supports 4 are grooved segments 13 in which a driving belt or cable 14 operates, such cable being suitably connected with an independent driving gear 15.

On the top of the frame 1 is disposed an inclined segmental pulp feed trough or launder 16 circumferentially disposed but leaving a blank space as at A during the interval of 105 which the rotating trays 8 will receive no pulp, but will be sprayed with clear water for the removal of the concentrates as will appear. A feed trough 17 may be used to carry pulp to the launder 16 from any desired point. An auxiliary launder or trough 18 leads from the launder 16 at intervals, say

of a length equal to the width of one or more of the trays 8, there being an inwardly projecting vane or dam 19 at each of said auxiliary troughs 18 for diverting a sufficient amount of the pulp into such members 18. From the auxiliary launders 18 extend a plurality of distributing launders 20, one set for each tier of trays 8, from each of which launders 20 a conduit 21 leads to a distributing plate 22, such plate having radiating ribs or riffles 23 for distributing its portion of the pulp equally along each adjacent segment of the inclined ring 6 from which it flows onto the concentrating trays 8. The construction just described is repeated for each of the said auxiliary distributors and each tier of trays as is necessary to complete operation. In the interval of blank space A, in which the trays 8 rotate without receiving a supply of pulp, are provided two clear water supply pipes 24 spaced apart on each side of the shelves or trays 8 and provided with spray pipes 25 and 25^a projecting out over the surface of the trays 8 and being so disposed as to spray thoroughly over the surface of such trays or shelves, the pipe 25^a being curved so as to spray the water over the interval of space necessarily occasioned by the supports 4.

Secured on the supports 4 below the lowest tier of trays 8 is a circumferentially disposed plate or floor 26 adapted to protect the pulp or concentrates from falling into and clogging up the rollers. Disposed around the entire machine below the outer periphery of the concentrating trays 8 is a tailing launder 27, said tailing launder having a grade to any desired point of discharge, and 28 is a concentrates trough or launder projecting outwardly from the outer periphery of the floor 26 and adjacent to the spray mechanism, said launder being adapted to receive the concentrated mineral and convey it to any desired point as fast as it is removed from the concentrating trays 8 by the combined action of the spray water emanating from the spray pipes 25^a and 25.

In using the device the pulp is fed into the launder 16 through the supply trough 17 and flows therefrom through the auxiliary launder 20 where it is distributed through the conduit 21 to the distributors 22 from which the ribs or riffles 23 spread the same evenly onto the inclined plate 6 from whence it spreads and flows onto the concentrating trays 8, said shelves or trays being of course rotated at the proper speed by means of the gear 15 and cable 14 bearing in the grooved segments 13. The pulp passes over the concentrating trays 8 on which are secured canvas or some other suitable textile fabric, and as the pulp flows over the trays or shelves 8 the coarser particles of valuable mineral find lodgment in the interstices of the concentrating fabric while the gangue and finer par-

ticles of mineral pass over the lower edge of the trays and fall into the tailing launder 27 where they are carried to any desired point, either to be classified and re-concentrated or discharged as waste. As the trays 8 rotate 70 the double system of stationary spray pipes 25 and 25^a spray clear water thereon, thus washing off the accumulated mineral into the concentrates launder 28 which conducts it to any desired point for commercial use.

The trays or shelves 8 with their concentrating surfaces may be adjusted by means of the adjustable band 10 to any desired inclination according to the character of the material or pulp being treated and the speed of 80 the rotations of the said trays may also be regulated as desired to secure the best results. The trays are made rectangular in shape and all of the same dimensions and are therefore readily interchangeable either from 85 one part of the same machine to another or from one machine to another. In this connection I wish to state that this is one of the important features of my invention as it enables me to quickly remove any undesirable 90 tray from a machine and substitute a suitable one without the necessity of stopping the machine, the removal being effected by simply raising the outer end of a tray to disengage the retaining hooks 9^a from the adjusting band 10 and drawing it out like a shelf, a part of the space A being designed for making any desired exchange of trays after they have passed the spray pipes 25 and 25^a and had the accumulated mineral 100 sprayed off.

While I have in this design shown and described my device as used for one or a single concentration, still in practice it may be adapted to perform multiple concentrations 105 on the same plant or on a duplication of plants, for the reason that when metalliferous ores are being pulverized preparatory to concentrating out and recovering the heavier particles of valuable mineral by wet concentration, a large percentage of the valuable minerals become so finely pulverized that they cannot be recovered by any single concentrating operation, for the reason that the quantity and force of water required to remove and discharge the coarser particles of waste gangue from the concentrating apparatus carries a part of the fine particles of mineral with it, which would be lost unless subjected to further concentration. A closer 110 saving of the valuable minerals can therefore be effected by subjecting the pulverized ore to repeated concentrating operations, sizing or classifying out and eliminating the coarser particles of waste gangue from the remaining 115 pulp after each successive concentration, before subjecting it to another one.

When the concentrating operations are to be effected by causing the pulp to flow over textile covered inclined planes as I do this in 120

design; it has been found that the greatest efficiency of the fabric may be obtained by using the new rough fabric for effecting the first concentration of the coarser particles of 5 valuable mineral, while old and smoother worn fabric on inclined planes set at a lower angle is more effective in collecting the finer particles of valuable mineral from the fine sands and sludges. Thus in using my improved concentrator, if desired for the sake 10 of economy, in the case of small installations each tier of trays may be provided with an independent pulp supply whereby the sized or classified pulp may be fed to said tables, 15 according to the degree of concentration desired, viz:—On certain tiers of the shelves or trays the concentrating fabric will be new and rough for concentrating the coarser particles of mineral from the coarse pulp, while 20 in other tiers will be inserted trays on which the fabric has become smooth from previous use in concentrating coarse pulp, the trays of course being adjusted to the desired inclination required for perfect concentration. Or 25 for large installations a duplication of entire plants would be used each one adjusted to treat a different class of material and the fabric covered trays would be either transferred from one plant to another as the concentrat- 30 ing fabric became worn or else each plant would be readjusted from time to time and a different class of pulp sent to it depending on the condition of the fabric on the trays. These constructions I have not shown in de- 35 tail in the drawings, since the principle set forth would not be departed from, but merely a duplication of the parts would be employed, hence I would be entitled to the full use thereof. This reclassifying and the 40 independent pulp supply means described above are old in the art and are shown in other patents, for instance the patent to Hambric No. 878879, Feb. 11, 1908, of which I am a part owner, and in other patents, 45 hence I will not specifically show or claim the same herein, but merely describe how the same might apply to this present application.

From the foregoing description it will be seen that I have produced a device which substantially fulfills the objects of the invention as set forth herein, viz:—a rotating frame containing a plurality of uniform rectangular adjustable removable and interchangeable shelves or trays adapted to be rotated around 55 a stationary centrally located pulp supply supplied with a simple and effective launder and distributing system. The uniform rectangular shape of the trays permits of a uniform flow of the pulp without forming mud 60 bars on the outer periphery of the trays as is the case with other devices having flaring sides to the tables to correspond with the segments of a circle, and the interchangeable construction of the trays permits of a more 65 compact construction than would be possible

if the concentrating fabric had to be removed or exchanged from tables in place, and also permits of the concentrating fabric being transferred from one machine to another without being detached from its fastening on 70 the tray when different grades of pulp are to be treated, so that the concentrating fabrics may be used for treating the class of pulp to which they are best adapted owing to the condition of their surface from previous wear. 75

While this specification sets forth in detail the present and preferred construction of the device, still in practice such deviations from such detail may be resorted to as do not form a departure from the spirit of the invention. 80

Having thus described my invention what I claim as new and useful and desire to secure by Letters Patent is:—

1. A concentrating apparatus comprising a plurality of circumferentially disposed upright supports carrying inwardly projecting arms spaced apart in tiers, each tier carrying a circumferentially disposed inclined ring, a plurality of circumferentially disposed trays 85 flexibly connected with said rings and being 90 adjustably supported by said rotating supports, and a pulp supply discharging on said trays.

2. A concentrating apparatus comprising a plurality of circumferentially disposed upright rotating supports carrying circumferentially disposed bands, adjustable vertically on said supports, a plurality of trays flexibly disposed on said supports and resting on said bands, and a pulp supply discharging on said 100 trays as set forth.

3. An apparatus of the character set forth comprising a plurality of upright supports roller mounted on a circumferentially disposed track, a plurality of grooved segments 105 on the upper ends of said supports, a cable operating in said segments, a driving gear engaging said cable, concentrating trays disposed on said supports, and a pulp supply discharging on said concentrating trays, as 110 set forth.

4. A concentrating apparatus comprising a plurality of rotating supports, a plurality of circumferentially disposed table sections on said supports projecting on either side of the same, water supply pipes disposed on either side of said tables such pipes having projecting discharge pipes extending over said tables and being spaced apart a sufficient distance to permit such upright supports to 115 pass therebetween, and a pulp supply discharging on said tables.

5. A concentrating apparatus comprising a plurality of rotating supports, a plurality of circumferentially disposed table sections 125 on said supports projecting on either side of the same, water supply pipes disposed on either side of said tables such pipes having projecting discharge pipes extending over said tables and being spaced apart a sufficient 130

distance to permit such upright supports to pass therebetween, one of said discharge pipes being curved so as to discharge the spray over the intervening space between 5 such discharge pipes, and a pulp supply discharging on said tables.

6. A concentrating apparatus comprising a plurality of rotating tables disposed in circumferentially arranged tiers each tier comprising a plurality of independent tables, a 10 stationary pulp supply disposed centrally with respect to said tables, a stationary segmental launder into which said pulp supply discharges an auxiliary launder leading from 15 said segmental launder intermediate each adjacent pair of tiers, a distributing launder leading from each of said auxiliary launders for each adjacent pair of tables in each tier distributing plates, such distributing launders discharging upon said distributing plates which distribute the pulp equally upon each 20 adjacent pair of tables in each tier.

7. A concentrating apparatus comprising

a plurality of rotating tables disposed in circumferentially arranged tiers each tier comprising a plurality of independent tables, a stationary pulp supply disposed centrally with respect to said tables, a stationary segmental launder into which said pulp supply discharges an auxiliary launder leading from 25 said segmental launder intermediate each adjacent pair of tiers, a distributing launder leading from each of said auxiliary launders for each adjacent pair of tables in each tier, such distributing launders discharging upon 30 each adjacent pair of tables in each tier, and a vane projecting partially across such segmental launder at the outlet of each auxiliary launder.

In testimony whereof I affix my signature 35 in presence of two witnesses.

WILTON E. DARROW.
